UNITED STATES PATENT OFFICE.

GEORGE W. REAM, OF CANTON, OHIO, ASSIGNOR TO THE BUCHER & GIBBS PLOW COMPANY, OF SAME PLACE.

DESIGN FOR A STANDARD FOR PLOWS.

SPECIFICATION forming part of Design No. 32,131, dated January 23, 1900.

Application filed December 2, 1899. Serial No. 739,057. Term of patent 14 years.

To all whom it may concern:

Be it known that I, GEORGE W. REAM, a citizen of the United States, residing at Canton, in the county of Stark and State of Ohio, have 5 invented and produced a new and original Design for a Standard for Plows, of which the following is a specification.

In the accompanying drawings, Figure 1 is an elevation of one side of the standard, while 10 Fig. 2 is a front view. Fig. 3 is a view of the side opposite to that of Fig. 1. Fig. 4 is a rear view.

The design resides in the configuration of the part of the standard shown in Figs. 1 and 15 2. The wing A extends rearwardly from the front edge of the standard and curves downwardly, making the face of the wing concave. The front line a of the standard is curved to

the point, while the rear line b of the wing is of irregular shape and connects with the approximately straight lower edge c, a notch d occurring at the intersection of the two lines. The concave face of the wing terminates at the line f, and from thence to the inclined and curved upper edge of the standard there is a 25 concave surface g. Fig. 3 shows the opposite face of the standard, and Fig. 4 shows a view taken from the rear.

What I claim is—

The design for a plow-standard as herein 30 shown and described.

GEORGE W. REAM.
